P. BROWN

ACTUATING MECHANISM FOR MAGNETOS

Filed Aug. 5, 1921

Patented Oct. 30, 1923.

1,472,545

UNITED STATES PATENT OFFICE.

PHELPS BROWN, OF SPRINGFIELD, MASSACHUSETTS.

ACTUATING MECHANISM FOR MAGNETOS.

Application filed August 5, 1921. Serial No. 490,078.

To all whom it may concern:

Be it known that I, PHELPS BROWN, citizen of the United States, residing at Springfield, in the county of Hampden and State 6 of Massachusetts, have invented new and useful Improvements in Actuating Mechanisms for Magnetos, of which the following is a specification.

This invention relates to an improved actuating mechanism for magnetos of the class wherein an armature is moved toward and away from a magnetic core to vary the flux flowing in a magnetic circuit. The movement of the armature in at least one 15 direction is accomplished relatively rapidly to produce a sudden change in the magnetic circuit and the production of a spark.

One object of the invention is to provide in a device of this character, improved means 20 for varying the time of actuation of the armature for the purpose of securing a retarded spark from the magneto when the cam shaft is rotating at relatively slow speeds and an advanced spark when the cam 25 shaft is rotating at a comparatively high speed.

Another object of the invention is to provide in a device of this character, an actuating means which is effective to permit 30 rapid movement of the armature at normal engine speeds and with little noise of operation but which is not so effective at very slow speeds, and a second actuating means which is effective independently of engine 35 speeds to permit rapid movement of the armature, but which is noise producing in operation, together with means for selectively operating the armature from either means.

A further object of the invention is to 40 provide independent armature actuating mechanisms, and means for rendering either mechanism effective to actuate the armature.

Another object of the invention is to provide in connection with an armature actuating 45 means mounted in fixed relation with the engine cam shaft, a device interposable between the armature and said means for varying the time at which said means is effective to move the armature.

Other objects of the invention will appear in the following description and in the 50 illustrative embodiment of the invention in the accompanying drawings, in which—

Fig. 1 is a side elevational view of a magneto with actuating mechanism, embodying 55 the invention, applied thereto;

Fig. 2 is a fragmentary end elevation of the same; and

Fig. 3 is a fragmentary side elevational view similar to Fig. 1 and showing a different relative positioning of the parts.

In the embodiment of the invention illustrated herewith, 10 designates a magneto, which may be of any desired construction, but, as shown, is of the general type disclosed in U. S. Letters Patent #1,307,843 granted to Phelps Brown on June 24, 1919. In this type of magneto, there are two cores 11 which are adapted to be connected by a vertically movable armature 12. Customarily, the armature 12 is moved relatively slowly toward the cores, but on the return movement is moved much more rapidly in order to produce a sudden change of flux in the magnetic circuit of which cores 12 75 form a part and it is this last named movement which results in the production of a spark from the magneto.

The driving mechanism for armature 12 generally comprises a cam which gradually 80 raises the armature and then suddenly releases it for movement at much higher speed by a driving spring (not shown herein but fully disclosed in the above-named patent). The armature is actuated from the cam by a member 13 which in its lower forked portion 15 carries a roll 14 to engage the cam. In order to obtain a quick release of the cam follower 14 and permit a very rapid movement of the armature entirely independent 85 of engine speeds, a cam, such as is shown at 20, has been employed, which cam has a radial let-off portion 24. A cam of this type, although desirable in that it permits movement of the armature entirely independent 90 of engine speed, is noise producing due to the free fall of the cam follower which it permits.

Experience has shown that at normal engine speeds a cam of the type shown at 19, 100 having a more gradual let-off portion 21, will permit a sufficiently rapid descent of armature 12 and will not produce the noise incident to cams like cam 20. At slow speeds, as on starting, the cam 19 will not 105 permit a sufficiently quick release of the armature to result in a spark of the desired intensity.

To reduce the noise of operation is important, and therefore a cam, such as cam 110 19 for example, is desirable and may be used without impairing the efficiency of the mag-

neto at normal speeds. On starting, however, a cam, such as 20, which is more noisy in operation, can be used without serious objection, for the noise will be of short duration and can be endured for the effectiveness of this type of cam at starting speeds. Therefore, I provide cams of both types and arrange to bring either one or the other into operation as desired.

- 10 Cam 19 is fixed to the cam shaft 17 and directly underlies the roll 14 as clearly shown in Fig. 2. On each side of cam 19 is a cam 20 and these two cams are fixed to shaft 17 and out of the path of roll 14. The 15 cams 20 are, however, arranged to underlie the two spaced arms 15 of the forked lower end of member 13 and the lower ends of these arms are, by preference, nicely rounded concentrically with roll 14.
- 20 The normal position of parts is shown in Fig. 3, wherein roll 14 bears on cam 19 and the rounded ends of arms 15 lie clear of the highest points on cams 20. To make cams 20 effective to operate armature 12, means, 25 as members 36, are interposed between the cams 20 and the rounded ends of arms 15, whereby the roll 14 is lifted free from cam 19 and the member 13 is lifted by engagement of members 36 with the arms 15. This 30 condition is illustrated in Fig. 1.

The members 36 form the two spaced arms of a fork-like member 34 and the latter is flexibly connected to a rod 25 slidably mounted in a bracket 27 stationarily secured 35 to some suitable means, as for example, the engine frame. The particular flexible connection shown between rod 25 and fork 34 consists of a closely wound coil spring 31, into one end of which the threaded end 30 of rod 25 is screwed, and the fork 34 is similarly held to the other end of spring 31 by a screw 32. Between the fork 34 and bracket 27 is a spring 37 which tends to move the fork toward the cams 19 and 21. The 40 bracket 27 is so located vertically as to guide the fork between the cams and roll 14 and so located horizontally that the arms 36 of the fork will straddle roll 14 and thereby be so positioned as to ride on the peripheries 45 of cams 20. The fork 34 is retractable manually and is held retracted by turning rod 25, when fully retracted, a quarter turn, which brings the bent portion 28 of rod 25 into engagement with an abutment 29 on 50 bracket 27. The bent portion 28 also by abutment with the hub portion of bracket 27, limits the degree of advancing movement of fork 34. In order to vary the outward 55 position of fork 36, and thus vary the time 60 at which it will be released by the radial surfaces 24 of cams 20, the bracket 27 is adjustably mounted, as by screws 41 which pass through longitudinal slots 40 in bracket 27 to permit movement of the latter toward 65 or away from cam 19.

In normal operation, the fork 34 is retracted, as shown in Fig. 3, and roll 14 rides on the periphery of cam 19. The cam shaft 17, turning in the direction of the arrow, shown in Fig. 1, gradually lifts roll 14 and raises armature 12 until it engages cores 11. As soon as roll 14 reaches the high point 22 of cam 19, the follower passes onto the incline 21 which connects the high point 22 with the low point 23 of cam 19. This incline, while not nearly as steep as the radial surfaces 24 of cams 20, will at normal engine speeds permit the cam follower 14 to descend under the force of the armature driving springs with sufficient rapidity to cause an effective break in the magnetic circuit and without producing the noise incident to a free fall of the follower 14. At 70 relatively low speeds and on starting, the cam 20 does not permit the desired rapid descent of the armature and, at such times, the fork 34 is released by disengaging the portion 28 from abutment 29 and turning it 75 ninety degrees into the position illustrated in Fig. 1. Thereupon spring 37 advances 80 the fork until its arms 36 straddle roll 14 and lie on cams 20. The member 15 is then lifted by cams 20 through the intermediary of the arms 36 of the fork, and the interposition of these arms hold roll 14 free from 85 cam 19. With this condition, a rapid descent of armature 12 is permitted as soon as the tips of arms 36 reach the radial surfaces 90 24 of cams 20, and this descent is entirely independent of the speed of shaft 17. This 95 driving arrangement, although noisy in operation, is effective on starting and since it is used only for short periods, the noise of operation is not a serious objection.

The use of an independent driving mechanism for starting and relatively slow engine speeds makes it possible to conveniently provide for the retarded spark desired from the magneto at such time, by setting the cams 20 so that their high points lie behind the 100 high point 22 of cam 19 in the direction of revolution of shaft 17. This provides for a 105 fixed degree of retardation of the spark.

The time of release of the armature 12, when actuated by cams 19, is not controlled 110 by their relative location but is determined by the position of fork 34 with relation to cams 19. Such position may be varied by adjusting the bracket 27 so that the release 115 of the armature will take place earlier or later than would be the case, with the parts positioned as shown in Fig. 1, accordingly as the bracket is moved to the left or the right 120 respectively.

The use of the interposable member 34 125 for varying the time of release of armature 12 is obviously capable of general application and is independent of the type of cam employed.

While the form of the invention shown 130

in the annexed drawings has been described with considerable particularity in order that the construction and operation of the same may be clear to those skilled in the art, it is to be understood that the invention is not limited to the precise details of construction shown and described, nor any of them, except as the same are included in the following claims.

10 1. What I claim is—

1. In a magneto actuating mechanism, a movable armature, a cam shaft, a cam carried by said shaft and adapted to actuate said armature, means interposable between 15 said cam and armature for actuating the latter from the cam, and supporting means for the last-named means having a flexible connection therewith.
2. In a magneto, a movable armature, a 20 drive shaft, two spaced cams thereon, a cam follower for the armature having a part normally directly engageable with one cam and an offset portion overlying the other cam but held from engagement therewith by 25 said part, and means interposable between the second cam and said offset portion to actuate the armature therefrom and to hold said part out of engagement with the first-named cam.
3. In a magneto, a movable armature, a 30

drive shaft, a cam thereon, an actuating member for the armature provided with spaced arms, a cam follower mounted between and extending beyond said arms for engagement with said cam, a cam on each side of the first cam and underlying said 35 arms, and a member having two spaced arms movable between said first named arms and last named cams to permit actuation of the armature from the latter and prevent its actuation by the first-named cams. 40

4. In a magneto, a movable armature, a drive shaft, a cam thereon, an actuating member for the armature provided with spaced arms, a cam follower mounted between and extending beyond said arms for 45 engagement with said cam, a cam on each side of the first cam and underlying said arms, and a member having two spaced arms movable between said first named arms and last named cams to permit actuation of 50 the armature from the latter and prevent its actuation by the first-named cams, means to hold said member disengaged from the last-named cams, and means to move said member on release of the last-named means to 55 ward said cams.

In testimony whereof I have affixed my signature.

PHELPS BROWN.
